NONCIRCULAR HOLE DRILLER
ATTACHMENT

Bernard Albert Woods, Forest Hills, Pa.

Application October 11, 1937, Serial No. 168,461

1 Claim. (Cl. 77—55)

This invention relates to an attachment for a drill for making non-circular holes, the general object of the invention being to provide a guide for the bit which causes the bit to make the hole 5 of a non-circular shape desired and yieldable means for holding the guide against the work piece, so that it is not necessary to connect the guide with the work piece, with means for supporting the guide in a movable manner from the 10 casing.

This invention also consists in certain other features of construction and in the combination and arrangement of several parts, to be herein-after fully described, illustrated in the accompanying drawing and specifically pointed out in the appended claim.

In describing the invention in detail, reference will be had to the accompanying drawing wherein like characters denote like or corresponding parts 20 throughout the several views, and in which:

Figure 1 is an elevation of a device for drilling a non-circular hole, with the invention applied thereto.

Figure 2 is a bottom plan view of Figure 1.

Figure 3 is a section on the line 3—3 of Figure 2.

In this drawing the numeral 1 indicates the casing of the drilling device which may be of the type shown in the patent to H. J. Watts No. 1,540,-30 826 dated June 9, 1925 or any other suitable type, wherein the bit 9 has lateral movement to a certain extent when the device is operated by the shaft 5. In such devices guiding means are provided for the bit to cause the same to drill a hole 35 of any desired non-circular shape in cross section and it is the object of my invention to provide improved means for so guiding the bit. Such means includes a supporting member or disk 10 having a socket therein for receiving a guiding 40 bushing 11 which guides the bit in its movement to form a hole of the same shape as that contained in the bushing. For instance by having the bushing provided with a square hole the bit will drill a square hole in a work piece or by 45 having the bushing of hexagonal shape the bit will make a hexagonal hole in the work piece. The bushing 11 is removably held in the supporting member 10 by a screw 12 passing through a hole 13 in the member 10. Bars 14 are connected at 50 their lower ends to opposite sides of the member 10 by the bolts 15 and the upper ends of these bars have the longitudinally extending slots 16 therein for receiving the bolts 17 projecting from the sides of the casing 1. A spring 18 has one end 55 fitting over the collar 3 of the casing 1 and its other end over a collar 19 on the member 10, said spring tending to press the member 10 away from the casing and thus this spring acts to hold the member 10 with the bushing 11 therein against

the work piece, thus avoiding the necessity of fastening the member 10 to the work piece. This manner of slidably connecting the member 10 with the casing of the drilling device and providing a spring for yieldingly holding the member 10 against the work piece enables a workman to turn out work much faster than where it was necessary to fasten the bushing carrying member to the work piece.

In order to use the invention on a device of the type shown in the before mentioned patent to H. J. Watts the casing 1 contains all the movable parts which are rotated by the shaft 5, and in order to hold the casing stationary during the 10 operation of the device a handle 20 is attached to the casing and extends at right angles therefrom so as to enable the workman to hold the casing against movement during the drilling operation. The device can be used for drilling any machine- 15 able material, such as brass, copper, bronze, steel, 20 etc.

Having described the invention, what is claimed as new is:

In a drill device for drilling non-circular holes and including a casing, a rotary member in the 25 casing, a bit connected with the rotary member and depending from the casing and a shaft extending into the casing and connected with the rotary member for rotating the same, a work 30 engaging member of considerable area and having its lower face flat for engaging the work and said work engaging member having a socket in its lower part and an opening extending from the top of the member to the upper end of the socket 35 for receiving the lower portion of the bit, said socket having an enlarged lower end, a bushing seated in the socket and having a non-circular hole therein for receiving the lower end of the bit 40 for guiding the bit, said work engaging member having a flange at its lower end fitting in the enlarged part of the socket with the lower face of the bushing flush with the lower face of the work 45 engaging member, means for removably holding the bushing in the socket, bars having their lower ends connected with the work engaging member and having elongated longitudinally extending 50 slots in their upper portions, bolts passing through the slots into the casing of the drill device, the upper face of the work engaging member having an annular centrally arranged projection thereon, a spring having one end fitting around said projection and its upper end engaging the lower end of the casing of the drill device for holding the work engaging member against a work piece 55 and a laterally extending handle connected with the casing for holding the casing stationary during the operation of the device.

BERNARD ALBERT WOODS.
